**FRAME FOR MINI-BIKES
AND THE LIKE**

Joseph E. Shannon, 117 Parkview Drive,
Whiteland, Ind. 46184

Filed July 12, 1972, Ser. No. 270,941

Term of patent 14 years

Int. Cl. D12—11

U.S. Cl. D12—111

Fig. 1

Fig. 2

Fig. 3

Fig. 4

Fig. 5

FIG. 1 is a top plan view of a frame for mini-bikes and the like, showing my new design.

FIG. 2 is a right side elevational view, the opposite side being substantially a mirror image thereof.

FIG. 3 is a rear elevational view thereof.

FIG. 4 is a front elevational view thereof.

FIG. 5 is a bottom plan view thereof.

I claim:

The ornamental design for a frame for mini-bikes and the like, as shown and described.
